METHOD FOR PROCESSING HYDROCARBON GAS

James B. Garner, Rolla W. Miller, and George B. Leyden, Pittsburgh, Pa., assignors to Standard Oil Development Company, a corporation of Delaware

Application March 10, 1927, Serial No. 174,143

3 Claims. (Cl. 48—196)

This invention relates to the processing of hydrocarbon gas such as natural gas for the production of illuminating and heating gases, and the like. In a preferred form of the invention, 5 a portion of a stream of natural gas is burned within that stream. The hydrocarbons are in this way modified by combustion, and also by heat produced from combustion. The gas produced is a diluted and altered mixture better 10 adapted for commercial use than the untreated gas.

The invention will be fully understood from the following description, read in connection with the accompanying drawing, in which

15 Fig. 1 is a diagrammatic vertical section through apparatus which we have devised for practicing the process; and

Fig. 2 is a transverse section on the line II—II of Fig. 1.

20 Referring to the drawing, reference numeral 1 denotes a tube or elongated reaction chamber, preferably lagged with asbestos 2, or otherwise thermally insulated. A burner 3 is mounted in one end of the tube. The burner, in the form shown, is composed of a base 4 and a neck 5, the opening 6 of which is small at the inlet and gradually flares outward. The base 4 has a central perforation 7 for entrance of the combustible mixture. A cap 8 closes the end of the 25 tube 1 and carries the base 4. The insulation 2 is preferably extended beyond the end of tube 1 and is arranged as shown to form a chamber 2'.

Pipes 9 and 10 respectively convey air and 30 gas to a venturi 11, or other mixing device, from which a pipe 12 leads to perforation 7. Pipe 12' supplies gas to the tube 1 through cap 8. Meters 13, 14, and 15, and valves 16, 17, and 40 18, are installed respectively in pipes 9, 10, and 12'. A thermostatic element 19 in the tube 1 is connected, as by suitable lever arms 20 and 21, to regulate a valve 22 in pipe 12. A pyrometer 19' is installed in the tube 1.

The end of tube 1 remote from the burner is attached to a cap 23. This has an end opening 45 24, opposite tube 1, and a lateral opening 25. A removable plug 26 is secured in opening 24 and a nipple 27 connects with opening 25. Nipple 27 leads into a pipe 28 which passes through a condensing coil 29. A pipe 30 leads from the 50 coil through a meter 31 to a gas holder (not

shown). A valved trap 32 is arranged in the pipe 30 for withdrawal of liquid.

A body of incombustible material 33 is placed in the tube 1 near the burner 5, for localizing the flame and other purposes, hereinafter referred to.

The method in a preferred form is as follows: Gas is admitted through pipe 10, valve 17, pipe 12 and burner 3 to expel the air from tube 1. The gas and air pass through pipes 28, 29 and 60 30, and are vented at a suitable point. After the air has been expelled, the plug 26 is removed and the gas is ignited as it issues from opening 24. Valve 16 in pipe 9 is opened to let air into the burner in limited amount, forming 65 a mixture in which the flame will "strike back" to the burner. The gas and air are mixed in the venturi 11. Valves 16 and 17 are adjusted so as to give a gas-air ratio suitable for complete combustion.

70 The plug 26 is then replaced and the tube 1 is heated by the burner flame to a temperature between about 700° and 1200° C. A temperature of around 800° C. is well adapted for most purposes. When the desired temperature is reached, valve 18 in pipe 12' is opened and natural gas 75 to be treated enters the tube 1.

Under the conditions stated the natural gas 80 undergoes considerable alteration. It appears that there is some decomposition or cracking of the gas, particularly the formation of olefins and hydrogen from paraffin hydrocarbons. The gas volume is increased. There is no substantial formation of carbon black or other solid reaction product.

85 The combustion within the tube 1 has two main functions, first to maintain a temperature to induce reaction in the main body of gas, and second to provide a diluent for that gas, in the form of combustion products. It is well known 90 that raw natural gas has too high a B. t. u. value for efficient use, and dilution is therefore desirable. Although a portion of the gas is burned in the present method, the net result is a gain, on account of increase of volume and better utilization of the heat value of the gas.

We prefer to prepare a gas of very low B. t. u. 95 value and mix this in the required proportion with raw natural gas. For example, one volume of gas is burned for one volume of gas treated. 100

The product (about 76 B. t. u.) is mixed with raw gas (about 1100 B. t. u.) to produce an 800 B. t. u. gas. Various other heat values may of course be produced.

5 The following examples show the effect of the process on a typical natural gas, such as the following:

Natural gas

10	Carbon dioxide	0.1	
10	Propane and higher hydrocarbon	0.3	
	Oxygen	0.0	
	Methane	94.7	
	Ethane	4.9	
15	Nitrogen	0.0	
	Total	100.0	
	B. t. u.	1105	

20 After treating, using 1 volume of gas for combustion to 4 volumes of gas for treating, at 900° C. and pressure sufficient only to carry the gas through the apparatus, analysis showed the following:

Treated gas

25	Carbon dioxide	5.1	
	Propane and higher hydrocarbons	2.1	
	Oxygen	0.1	
	Hydrogen	7.0	
30	Carbon monoxide	6.0	
	Methane	19.0	
	Nitrogen	60.7	
	Total	100.0	

35 This composition of the treated gas is characteristic for gases which underwent partial combustion, inasmuch as it still contains a substantial amount of methane.

40 The process may be carried out under pressure. The incombustible material 33 (broken gas radiants, chips of fire brick, etc.) localizes the flame and distributes the heat. Other kinds of refractory materials may be used, as well as catalytic substances.

45 It is desirable to control automatically the

amount of combustion taking place and this may be done by means of the thermostatic element 19, through its control of the inlet valve 22.

Various changes and alternative arrangements may be made within the scope of the appended claims, in which it is our intention to claim all novelty inherent in the invention as broadly as the prior art permits.

We claim:

1. The method of treating natural hydrocarbon gas of a given B. t. u. value, which comprises mixing a portion of the gas with up to the theoretical amount of air required for complete combustion, burning the mixture in a reaction zone whereby the zone is maintained at a temperature between 700° C. and 1200° C., passing another portion of the hydrocarbon gas into and through the heated reaction zone while continuing said burning whereby the gas is cracked and mingled with the products of combustion, and collecting the resulting gaseous products of relatively lower B. t. u. value per unit volume.

2. The method according to claim 1 in which approximately four times as much hydrocarbon gas is introduced separately into the reaction zone as is introduced in the mixture of air and gas.

3. The method of treating natural hydrocarbon gas of a given B. t. u. value, which comprises mixing a portion of the gas with up to the theoretical amount of air required for complete combustion, burning the mixture in a reaction zone whereby the zone is maintained at a temperature of approximately 800° C., passing another portion of the hydrocarbon gas into and through the heated reaction zone while continuing said burning whereby the gas is cracked and mingled with the products of combustion to produce a gaseous mixture having a B. t. u. value of approximately 800, and collecting the resulting 115 800 B. t. u. gaseous mixture.
